STOCKING

Robert E. Davis, Fort Payne, Ala.

Application April 19, 1937, Serial No. 137,854

11 Claims. (Cl. 66—178)

This invention relates to the manufacture of hosiery, and particularly to men's half hose. The sock of the present invention is composed of plain knit fabric throughout, as distinguished from a sock constructed in part of true ribbed fabric. The sock of the present invention includes a special elastic top, a plain leg, and a full fashioned foot, with sole, heel, and high splice reinforcements.

10 The object of the present invention is to knit the elastic top, the plain leg, and the reinforced heel on a circular knitting machine, as a seamless tube; and to knit the full fashioned foot on a different machine in the form of a selvage edged blank, fashioned by transferring stitches inwardly from the opposite edges of the blank.

20 The construction and mode of manufacture of hosiery in accordance with the present invention will be fully disclosed hereinafter, reference being had to the accompanying drawing, of which:

Fig. 1 is a side elevation of a complete sock; Fig. 2 is a portion of the seamless tube as it comes from the circular knitting machine;

25 Fig. 3 is a view of the tube section of Fig. 2 split longitudinally throughout a portion of its length with the selvage edged foot blank knit thereto, prior to the closing of the foot and leg to complete the stocking shown in Fig. 1; and

30 Figs. 4 and 5 are views illustrating steps in preparing the tube for knitting the foot of the stocking thereto.

As shown in Fig. 1, the stocking comprises a leg portion 1, a special elastic top 2, a full fashioned foot 3, a heel 4, high splice reinforcement 5 above said heel, a reinforced sole 6 extending forwardly from the heel 4 and a box-toe 7.

35 The extreme forward end of the box-toe 7 of the stocking has corresponding portions of the opposite edges of the foot blank looped together to close the toe of the stocking, as indicated at 8. The lower portion of the heel 4 is also closed by looping corresponding portions of the opposite edges of the foot blank together, as indicated at 9. The stocking is provided with a seam extending along the under part of the foot from the looped end 8 of the toe 7 to the forward edge of the heel 4, as indicated at 10. In the 40 present instances, the sock also has a seam extending up the back of the leg from the rear lower edge of the heel 4, substantially to the lower part of the elastic top 2, as indicated at 11.

45 According to the principles of the present invention, the leg 1, top 2, heel 4, high splice 5

and the upper part 12 of the instep portion of the stocking lying in front of the high splice 5 are all knit integrally on a circular knitting machine, preferably one of a type equipped to produce normal split sole stockings.

5 In accordance with the principles of the present invention, the machine produces a continuous tube A having pairs of diametrically opposite selvage edged slits a, a formed therein and extending longitudinally or walewise of the tube A, 10 in spaced relation to each other longitudinally of said tube.

15 At one end of each pair of slits a, a, and extending coursewise or transversely of the tube A, are formed loose courses or other marking lines 15 a¹, a¹ which divide the tube into a plurality of leg blanks A¹, A¹.

20 Extending coursewise around one side of the tube A, from one slit a to the other slit a of each pair, and walewise from the marking line or loose course a¹ at the lower ends a² of the slits a, a throughout the lengths of the slits a, a and beyond the upper ends a³, a³ of the slits a, a, the tube A is knit with a reinforcing thread in addition to the regular knitting thread, to provide a reinforced area b in the tube, which, in the finished stocking, constitutes the heel 4 and the high splice reinforcement 5.

25 At the end of the tube section or leg blank A, opposite to that in which the slits a, a are formed, a rubber strand 15 is incorporated in the plain fabric of the tube A in a series of spiral convolutions 16. The opposite terminal ends 17 and 18 of the elastic strand 15 are anchored in the plain fabric by being knit into one or more stitches of the fabric, to prevent the ends of the rubber strand from pulling away from the anchor points 17 and 18. The rubber strand 15, in a like manner, is anchored in the fabric at 30 relatively spaced wales, in relatively spaced courses of the stitches of which the fabric is composed, as clearly shown and described in my co-pending applications eSerial No. 759,831, filed December 31, 1934; Serial No. 28,463, filed June 26, 35 1935; Serial No. 34,328, filed Aug. 2, 1935; and Serial No. 41,849, filed Sept. 24, 1935.

40 With the elastic strands 15 being introduced and incorporated in the fabric under tension the portions of the tube A in which said elastic is introduced are contracted transversely. This causes these wales of the plain fabric to which the elastic strand is attached to be pulled or drawn together laterally, thereby producing a 45 ribbed effect and which as a matter of identifi- 50 55

cation is hereinafter referred to as an elastic mock-rib top 2.

Between the upper anchorage 18 of the rubber strand 15 and the next severing line a^1 the tube 5 A is provided with a plain fabric section c, corresponding to the plain fabric of which the leg 1 is composed.

In the side of the tube A in which the instep portion 12 of the leg 1 is formed, and extending 10 from the severing line a^1 at the lower ends of the slits a, a to the opposite end a^3 of the slits a, a, is provided with a section of fabric d which, as will be later described, is subsequently raveled away from the line a^1 to the line a^4 .

15 The opposite edges a^5 and a^6 of the slits a, a are selvage edges which are produced by reciprocatory knitting in those sections of the tube lying between the lines a^1 and a^4 . This is made possible by the employment of the split sole 20 mechanism of the circular knitting machine in a manner which will be obvious to one skilled in the art.

After the tube A is formed and cut into sections A¹, A¹, along the lines a^1 , a^1 , the tube sections A¹, A¹ are each split longitudinally, through the side thereof in which the reinforcement b is formed, midway between the slits a, a, from the severing line a^1 at the lower ends a^2 of the slits a, a to a point approximately adjacent or below the anchorage point 17 of the rubber strand 15.

A line for splitting the tube longitudinally may be readily produced by a drop stitch or by leaving out a needle.

35 Fig. 3 illustrates the tube section A¹ as having been split as above described, with the split end of the tube opened up and spread in a substantially flat plane, in which position the inner edges a^5 , a^6 of the heel pieces 4 are turned at right 40 angles to the wales and placed in line with the course of stitches which coincides with the instep line a^4 , which extends between the upper ends a^3 , a^3 of the slits a, a. The upper ends a^3 , a^3 of the slits a, a represent the turning points of the 45 heel tabs 4, 4. The fabric d is raveled out from the line a^1 to the line a^4 after the course of stitches which coincides with the line a^4 are applied to the needles of the footer. The foot 3, with its plain top 13 and reinforced sole areas 50 6, 6 at the opposite sides thereof and the reinforced box-toe 7 are then formed in the manner common to the production of full fashioned feet, by which extreme outer stitches are transferred inwardly at predetermined courses to produce 55 selvage edges 14, 14 on the foot blank.

The blank is then folded until the edges 14, 14 of the foot and the edges 19, 19 of the leg, produced by splitting the tube longitudinally, as above noted, lie in coinciding relation to each 60 other, whereupon the seams 10 and 11 and the looped sutures 8 and 9 are formed to close the foot and leg of the stocking.

65 Preferably, the tube sections A¹, A¹ are not split through the mock rib tops 2, which remain intact in tubular form. The fabric c between the anchor point 18 of the elastic strand 15 and the cutting line a^1 adjacent thereto is then turned inwardly and stitched or looped to the inside surface of the top 2 by any suitable form of elastic 70 connection such as may be produced by a zig-zag or flat lock sewing machine and indicated at 20 in Fig. 1.

I claim:

75 1. A leg blank comprising a continuous seam- less tube of plain knit fabric having diametrical-

ly opposed elongated narrow openings extending longitudinally of said tube inwardly from one end thereof and dividing the tube throughout the full length of said openings into two similar semi-circular selvaged edge portions disposed at opposite sides respectively of said openings, and an elastic strand extending transversely of the tube in a region adjacent the opposite end of the tube and anchored in said fabric solely at relatively spaced points transversely and longitudinally of 10 said tube.

2. A leg blank comprising a continuous seam- less tube of plain knit fabric having diametrical- 15 ly opposed elongated narrow opening extending longitudinally of said tube inwardly from one end thereof and dividing the tube throughout the full length of said openings into two similar semi-circular selvaged edge portions disposed at opposite sides respectively of said openings, and an elastic strand extending transversely of the tube in a region adjacent the opposite end of the tube and anchored in said fabric solely at relatively spaced points transversely and longitudinally of 20 said tube and under tension sufficient to contract said end of said tube below the normal diameter 25 of the tube.

3. A leg blank comprising a continuous seam- less tube of plain knit fabric having diametrical- 30 ly opposed elongated narrow openings extending longitudinally of said tube inwardly from one end thereof and dividing the tube throughout the full length of said openings into two similar semi-circular selvaged edge portions disposed at opposite sides respectively of said openings, a reinforced area extending around one side of said tube from 35 one of said openings to the opening opposite thereto, and an elastic strand extending transversely of the tube in a region adjacent the opposite end of the tube and anchored in said fabric solely at relatively spaced points transversely and longi- 40 tudinally of said tube.

4. A leg blank comprising a continuous seam- less tube of plain knit fabric having diametrical- 45 ly opposed elongated narrow openings extending longitudinally of said tube inwardly from one end thereof and dividing the tube throughout the full length of said openings into two similar semi-circular selvaged edge portions disposed at opposite sides respectively of said openings, a reinforced area extending around one side of said 50 tube from one of said openings to the opening opposite thereto throughout the full length of said openings, and an elastic strand extending trans- versely of the tube in a region adjacent the oppo- site end of the tube and anchored in said fabric 55 solely at relatively spaced points transversely and longitudinally of said tube.

5. A leg blank comprising a continuous seam- less tube of plain knit fabric having diametrical- 60 ly opposed elongated narrow openings extending longitudinally of said tube inwardly from one end thereof and dividing the tube throughout the full length of said openings into two similar semi-circular selvaged edge portions disposed at opposite sides respectively of said openings, a reinforced area extending around one side of said 65 tube from one of said openings to the opening opposite thereto throughout the full length of said openings and to a predetermined distance beyond the inner ends of said openings, and an elastic strand extending transversely of the tube in a region adjacent the opposite end of the tube and anchored in said fabric at relatively spaced 70 points transversely and longitudinally of said tube.

6. A leg blank comprising a seamless tube of plain knit fabric, an elastic strand incorporated in and extending transversely of said tube in a region adjacent one end of said tube and anchored in said plain fabric solely at relatively spaced wales in relatively spaced courses of stitches of which said region is composed, and a single longitudinally extending appendage projecting from the opposite end of the tube around substantially one-half of the circumference of the tube.

7. A leg blank comprising a seamless tube of plain knit fabric, an elastic strand incorporated in and extending transversely of said tube in a region adjacent one end of said tube and anchored in said plain fabric solely at relatively spaced wales in relatively spaced courses of stitches of which said region is composed, and a single longitudinally extending appendage projecting from the opposite end of the tube around substantially one-half of the circumference of the tube with the longitudinal edges of said appendage formed completely with selvages.

8. A leg blank comprising a seamless tube of plain knit fabric, an elastic strand incorporated in and extending transversely of said tube in a region adjacent one end of said tube and anchored in said plain fabric solely at relatively spaced wales in relatively spaced courses of stitches of which said region is composed, and a single longitudinally extending appendage projecting from the opposite end of the tube around substantially one-half of the circumference of the tube with the longitudinal edges of said appendage formed completely with selvages and with said appendage reinforced from the extreme end of said appendage to the stitch course of said tube intersecting said edges of said appendage.

9. A leg blank comprising a seamless tube of plain knit fabric, an elastic strand incorporated in and extending transversely of said tube in a region adjacent one end of said tube and anchored in said plain fabric solely at relatively spaced wales in relatively spaced courses of stitches of which said region is composed, and a single longitudinally extending appendage projecting from the opposite end of the tube around substantially one-half of the circumference of the tube with the longitudinal edges of said appendage formed completely with selvages and

with said appendage reinforced from the extreme end of said appendage to the stitch course of said tube intersecting said edges of said appendage, said reinforcement extending up into said tube beyond said stitch course.

10. The process of making hosiery blanks which consists in knitting a seamless tubular leg blank and incorporating in a region adjacent one end thereof an elastic strand, anchoring said elastic strand solely at points spaced circumferentially and longitudinally of said region of said blank, forming longitudinally extending openings at opposite sides respectively of the tube at and to a predetermined distance inwardly from the second end of said blank, and raveling out the fabric between the openings at one side of the tube from said second end of the blank to a stitch course intersecting said openings substantially at the bases of said openings to produce a single appendage at the diametrically opposite side of the blank provided with longitudinally extending selvage edges formed by said openings to prepare said blank for knitting a full fashioned foot to said edges and to the intersected course between said openings.

11. The process of making hosiery blanks which consists in knitting a seamless tubular leg blank and incorporating in a region adjacent one end thereof an elastic strand, anchoring said elastic strand solely at points spaced circumferentially and longitudinally of said region of said blank, maintaining said elastic strand under sufficient tension to contract said region of said blank circumferentially to a diameter less than the normal diameter of the tube, forming longitudinally extending selvage edge openings at opposite sides respectively of the tube at and to a predetermined distance inwardly from the second end of said blank, raveling out the fabric between the openings at one side of the tube from said second end of the blank to a stitch course intersecting said openings substantially at the bases of said openings to produce a single appendage at the diametrically opposite side of the blank provided with longitudinally extending selvage edges formed by said openings, to prepare said blank for knitting a full fashioned foot to said edges and to the intersected course between said openings.

ROBERT E. DAVIS.
